UNITED STATES PATENT OFFICE.

FRANK D. RIFNER, OF DAYTON, OHIO.

METAL-WORKING DEVICE.

Application filed May 25, 1925. Serial No. 32,600.

To all whom it may concern:

Be it known that I, FRANK D. RIFNER, a citizen of the United States of America, residing at Dayton, county of Montgomery, 5 and State of Ohio, have invented certain new and useful Improvements in Metal-Working Devices, of which the following is a full, clear, and exact description.

This invention relates to improvements in 10 metal working devices and particularly to such devices used for drawing sheet metal.

It is among the objects of the present invention to provide a device, sturdy in structure and simple in design, which will eliminate crinkles in the sheet metal stock as it 15 is drawn, thereby producing an even and smooth surface on the object produced.

Such a machine has been shown in the drawings of the present application as including male and female die members; a pressure plate adapted to move by gravity, into engagement with the sheet metal on the female die member, upon approaching movement of the male die member toward 25 the sheet metal; and means, including pivoted locking levers and a cam for operating said levers, for securely locking the pressure plate in this sheet-metal-engaging position during the drawing operation.

Further objects and advantages of the 30 present invention will be apparent from the following description, reference being had to the accompanying drawings, wherein a preferred form of the present invention is clearly shown.

In the drawings:

Fig. 1 is a perspective view of the device. Certain parts have been broken away to save space on the drawings.

Fig. 2 is a fragmentary front view showing the wedge-shaped cam in the extreme down position, between the camming levers.

Fig. 3 is a view similar to Fig. 2, the 45 wedge-shaped cam being shown in the position where the camming levers have started to release the clamping plate.

Fig. 4 is a section through the female die member at 4—4 of Fig. 3, and shows the 50 camming levers adjusting device.

Fig. 5 shows the device attached on a punch press.

Fig. 6 is a fragmentary side view of the device as shown in Fig. 2.

Referring to the drawings, and particularly to Fig. 5, the numeral 20 designates the base plate of the punch press; 21 the vertical standards which support the crank-shaft 22, driven by means of a pulley 23. A crank arm 24 connects the crankshaft 22 55 with a drop head 25 slidably supported on the vertical standards 21.

The sheet-metal-drawing device comprises a male die member 26, carried by or formed integral with a plunger block, is adapted to 60 be inserted in the drop head 25 of the punch press, for securing the male die member to said drop head. On one side of the plunger block 27 there is secured a cam element 29 by means of stud 30, while on the direct 65 opposite side of said plunger block, a similar cam 31 is supported by means of stud 32. These cams are parallel with the male die member 26, said cams having opposite camming surfaces 33 and 34 directly parallel for a predetermined distance, then converging to form a wedge-shaped operating portion, as shown at 35, for purposes to be described.

The female die member designated by the 70 numeral 36, includes oppositely disposed feet 37 and 38, said feet being each provided with a slot for receiving studs 39 and 40, for the purpose of securing the female die member to the base plate 20 of the punch press. The 75 female die may also be secured in a block, in which case the block would comprise the elements 36, having feet 37 and 38, the female die member being secured in the block in any suitable manner.

Interposed between the plunger block 27 and the female die member 36, is a pressure plate 41, having a central aperture through which the male die member 26 is adapted to pass. On each side of the male die member 26 there is provided comparatively long studs 42, one end of these studs being screwed into the plunger block 27. Both studs pass through holes formed in the pressure plate 41 and the free ends of the studs are provided with head portions. This is clearly illustrated in Fig. 6. From this it can be seen that when the plunger block 27 moves upwardly away from the female die 80

90

95

100

- member, the studs 42 will move through the holes in the pressure plate 41 until the heads of said studs engage with the bottom surface of the pressure plate, at which time said pressure plate will be moved upwardly with the plunger block 27, thus moving said pressure plate away from the female die member. Upon return movement of the plunger block 27 toward the female die member 36, the pressure plate 41 will move downwardly with the studs 42, until said plate engages with the sheet metal positioned on the female die 36, at which time continued movement of the plunger block downwardly will tend to move the studs 42 through the plate 41, the heads of the studs 42 entering the passages provided in the female die member for that purpose.
- The pressure plate 41 is provided on its one side with a recess, the upper edges of this recess being beveled off as at 46, for purposes to be described. On the direct opposite side of the pressure plate 41, a similar recess is formed.
- A pair of levers 47 and 48 are pivotally supported on each one of the opposite sides of the female die member 36. They are held in position on the plate by means of nuts 49 and 50. These levers, when in their inoperative position, are drawn together by means of a spring 51 which is anchored on studs formed integral with nuts 52 and 53. The nut 52 supports a roller 54 adjacent the free end of the lever 47, while the nut 53 supports the roller 55 adjacent the free end of the lever 48. The levers on the opposite side of the female die member 36 are similarly provided. Each lever is provided with a sloping surface 56, on its outer edge and so positioned that said sloping edge 56 may engage with the beveled edge 46 of the respective recess formed in pressure plate 41 under conditions which will be explained hereinafter.
- In order to adjust the relative position of the sloping surfaces 56 of the various levers to the position of the pressure plate 41, when in engagement with the sheet metal, an adjustable support is provided for the directly opposite levers of each pair. This adjustable support is clearly illustrated in the Fig. 4, and comprises a central bearing portion 60, adapted to fit in a transverse passage formed in the female die member 36.
- On one side of the die member 36 the supporting member is provided with a bearing portion 61, eccentric to and larger than the portion 60. The lever supported on the female die member 36 directly opposite the die member 48 and which may be designated 48^a, is carried by the portion 61 and held in position between the female die member 36 and a head 62 formed integral with the portion 61. On the opposite side of the female

die member and extending beyond the surface thereof, is a portion 63 eccentric to but smaller in diameter than the portion 60 of the supporting device. This portion 63 has a flat surface 64 formed thereon, which prevents rotation of the collar 65 fitting on this portion 63. The collar 65 is of equal outside diameter to the portion 61 and acts as a bearing for the lever 48. The nut 50 is screwed onto the screw-threaded portion 66 formed on the portion 63; thus, said lever 48 is held in position between the female die member 36 and the nut 50. When adjustments of the levers are desired, the nut 50 is loosened and the head portion 62 is rotated. Thereby rotation of the portion 60 and the die 36 will either throw the portions 61 and 63 upwardly or downwardly, depending upon the direction of eccentricity, thereby moving the levers upwardly or downwardly, respectively, and consequently reducing or increasing the space between the beveled surface 56 and the surface of the female die member 36.

The operation of the device is as follows:

When the male die member 26 is in the position as shown in Fig. 3, the cam 29 is just moving from between the rollers 54 and 55 carried on levers 47 and 48. This is also true of the cam on the opposite side of the plunger block 27. Continued movement upwardly of the male die member will permit the spring 51 to move the rollers 54 and 55 into engagement, thereby moving the sloping surfaces 56 away from the edges of the recess 45 so that when the heads or studs 42 engage with the pressure plate 41, moving it upwardly, the levers 47 and 48 will clear the edges of the recess in the pressure plate. A piece of sheet metal is then inserted in the die, lying directly on the female die member 36. Now, when the male die member moves downwardly, the pressure plate 41 will move by gravity with the studs 42 until said plate comes to rest on the sheet metal lying on top of the female die member. At this time the cam element 29 will have its wedge-shaped portion 35 entering between the rollers 54 and 55 and tending to move them away from each other, so that the sloping surfaces 56 of each of the rollers will be moved outwardly to engage with its respective beveled edge of the recess 45, in which the rollers are now positioned. The adjusting element on the levers having been set for the thickness of the metal to be used in the die, the rollers when engaging with the parallel surfaces 33 and 34 of the cam 29, will hold the levers 47 and 48 in such a position where their respective sloping surfaces 56 will lock with the beveled edges 46 and the recess, thereby locking the pressure plate 41 in the position on the sheet metal. From this it will be seen that the sheet metal

lies between two non-yielding rigid walls formed by the upper surface of the female die member 36 and the lower surface of the pressure plate 41.

5 During the entire drawing operation the parallel surfaces 33 and 34 of the cam 29 will maintain the levers 47 and 48 in a constant position.

It may clearly be seen that when thinner metal is desired to be drawn, the adjusting element shown in Fig. 4 may be operated to move the levers 47 and 48 and the corresponding levers, downwardly. Thus, the pressure plate 41 will be clamped or locked 10 in a position closer to the female die member 36. Opposite adjustment of the element will set the device to lock at a greater distance between the pressure plate and the female die member.

20 Previous practice provided springs, rubber or air pressure on a pressure plate for holding the sheet metal against the female die member during operations, and in these devices as the plunger moved downwardly, 25 the pressure on the pressure plate was increased. This is entirely eliminated in the present structure. Here the pressure plate is permitted to drop by gravity onto the metal, the only pressure on the metal being 30 the weight of the pressure plate. As soon as this pressure plate comes to rest on the metal, locking devices are brought into effect for locking this pressure plate in this position. No extra pressure is exerted on 35 the pressure plate by this locking operation. In the old devices, the provision of springs, rubber or air on the pressure plate, provided a yieldable pressure on the pressure plate, so that it was possible to move the 40 pressure plate away from the female die member, due to this yielding pressure on top of the plate. However, in the present structure the pressure plate is held non-yieldingly in position on the sheet metal, 45 still not exerting any undue pressure on the metal while it is being drawn.

In a portion of the description of the operation, reference is made to the pair of levers on one side of the female die member only. It will, of course, be understood that the levers on the opposite side of the die member are correspondingly operated and correspondingly lock the opposite side of the pressure plate in position.

55 While the form of embodiment of the invention as herein disclosed, constitutes a preferred form it is to be understood that other forms might be adopted, all coming within the scope of the claims which follow.

What is claimed is as follows:

1. A device for drawing sheet metal comprising, in combination, a die including male and female members; a pressure plate

adapted to be moved into engagement with 65 the metal on the female die member; and a pressure-plate locking means provided on each one of two opposite sides of the die, each of said locking means including a pair of locking levers adjustably secured to the 70 female die member, and wedges rigidly mounted on the male die member and adapted to be inserted between their respective pair of locking levers whereby said levers will concurrently be moved in opposite directions and into locking engagement with the pressure plate. 75

2. A device for drawing sheet metal comprising, in combination, a die including male and female members; a pressure plate 80 adapted to be moved into engagement with the metal on the female die member; and a pressure-plate locking means provided on each one of two opposite sides of the die, each of said locking means including a pair 85 of locking levers adjustably secured to the female die member for each pair of levers, and a single wedge-shaped member having a variable dwell and a constant dwell and adapted to be inserted between its respective pair of locking levers whereby said levers are concurrently moved apart and into proper engagement with the pressure plate and then constantly held in this proper 90 pressure-plate-engaging position. 95

3. A device for drawing sheet metal comprising, in combination, a die including male and female members; a pressure plate adapted to be moved into engagement with the metal on the female die member; and a pressure-plate locking means provided on each one of two opposite sides of the die, each of said locking means including a pair of locking levers, each lever having its one end pivoted to the female die member and provided with a roller at its other end, and including a wedge-shaped cam rigidly mounted on the male die member and having diverging surfaces and parallel surfaces which when the said cam is inserted between 110 the rollers of its respective pair of levers will first move the both of said levers apart and into proper pressure-plate engagement and then constantly hold said levers in this proper position. 115

4. A device for drawing sheet metal, comprising in combination, male and female die members; a pressure plate adapted to be moved into engagement with the sheet metal on the female die member; a pair of locking levers provided on each one of the two opposite sides of the female die member; and common means for adjustably and pivotally supporting the directly opposite levers of each pair of levers on the female die member, thereby permitting simultaneous adjustment of both said levers. 120 125

5. A device for drawing sheet metal, com-

prising in combination, male and female die members; a pressure plate adapted to be moved into engagement with the sheet metal on the female die member; a pair of locking levers pivotally supported on each one of the two opposite sides of the female die member; and eccentric adjusting means extending through the female die member, each carrying the two directly-opposite levers of each pair of levers, said means being adapted to simultaneously adjust their respective two levers of each pair of levers. In testimony whereof I hereto affix my signature.

FRANK D. RIFNER.
